UNITED STATES PATENT OFFICE.

FRANK W. WOOD, OF MONTCLAIR, NEW JERSEY.

MEANS FOR INDICATING THE INTEGRITY OF CIRCUITS.

Application filed February 27, 1919. Serial No. 379,840.

To all whom it may concern:

Be it known that I, FRANK W. Wood, a citizen of the United States, residing at Montclair, in the county of Essex and State of New Jersey, have invented new and useful Improvements in Means for Indicating the Integrity of Circuits, of which the following is a specification.

This invention relates to means for indicating the integrity of circuits, pertaining more particularly to circuits of the alternating current type, and especially to conditions present where the indicating mechanisms of a plurality of independent circuits may be located in juxtaposition.

The invention is capable of rather wide application, but for purposes of explanation of the problems presented and solved by its use under onerous conditions, a brief description is given of its installation in connection with the running-light circuits of ships.

The number of circuits employed in installations for this purpose may be large—in some instances as many as nine different circuits in parallel may be utilized, each circuit controlling the operations of one or more lamps. When in service it is essential that the lamps be illuminated constantly for safety purposes, but such constancy is, of course, dependent on the lamp itself—if burned out the signal effect of the lighted lamp is lost; it therefore becomes essential that a new lamp be substituted as quickly as possible.

To meet these conditions it has been the practice to install the systems in such manner as to provide a reserve lamp in position, with the lamp circuit for a particular position divided to place the two lamps in parallel, utilizing a conveniently-positioned switch to control the activity of one or the other of such parallel circuits. And since it is inconvenient to provide an attendant to watch the lit lamp, it has been the practice to provide an automatic indicator—generally in the form of a relay in series with the lamp—which will give instant notice of the breaking of a circuit by the burning out of the lamp, the switch being located to permit its being rapidly thrown to render the reserve lamp active, the burned-out lamp being replaced at leisure.

Heretofore it has been the practice to utilize direct current for supplying these

different circuits, and to permit of minimum attention the switches and relays have been assembled at one point—the leads being brought to that point—where suitable indicating mechanisms can be installed to permit observation by a single observer, the mechanisms sometimes including both audible and visual signals. This has been made possible through the use of direct current supply.

Recent installations of lighting apparatus have, however, employed alternating current as the source of supply, raising certain problems in the operations of the indicating system described, these problems being due to the difference in action provided by the substitution of alternating for direct current in these circuits. This difference is made apparent more particularly in the relays used in the circuits, the change in type of current setting up conditions of humming, chattering, etc., in these relays to such an extent as to be extremely disagreeable, and where a multiplicity of these circuits are employed, this noisy condition becomes so burdensome as to generally cause the system to be cut out of operation, thereby preventing the operation of the signals and eliminating the safety factor provided by the automatic operation intended.

It is to meet conditions of this kind that formed the basis of the present invention, by making it possible to utilize the general characteristics of the system but to make it operate under the change in type of current and practically noiseless—excepting when the audible signal is intentionally operated. The problems are met by the use of a relay structure operative noiselessly in alternating current circuits, and the particular development of the present invention pertains more particularly to such relay. Another feature is that of practically combining the visual signal with the relay to provide a compact indicating mechanism.

Other objects are to provide a general construction, which is simple and efficient in operation, durable in construction, and which can be manufactured and installed at relatively low cost.

To these and other ends, the nature of which will be readily understood as the invention is hereinafter disclosed, said invention consists in the improved construction and combination of parts hereinafter fully

described, illustrated in the accompanying drawings, and more particularly pointed out in the appended claims.

In the accompanying drawings, in which similar reference characters indicate similar parts in each of the views,—

Figure 1 is an end elevation of a relay and indicator constructed in accordance with my invention.

Fig. 2 is a longitudinal sectional view of the same, parts being shown in elevation.

Fig. 3 is a top plan view.

Fig. 4 is a diagrammatic view illustrating a manner of use.

In describing the invention I will first explain the general construction of the relay, it forming a controlling factor of the invention since it must be operative within the alternating current circuit and must be of a type which will solve the difficulties inherently present when operating under these conditions.

10 designates the laminated core of an electromagnet, the coils being indicated at 11 and shown as mounted on the legs of the core, the particular embodiment showing the core contour as generally U-shaped. The ends of the legs provide the poles of the 20 magnet, the polar faces being on the inner faces of the legs and made up of the exposed edges of the laminations. The polar faces are arranged approximately on the arcs of a circle, thus making them concentric to an 30 axis located midway between the faces and which lies in the magnetic field of the magnet when the coils are energized.

The core is supported on a suitable base 12 by suitable members, indicated as pedestals 13, spacing the polar faces from the base a suitable distance. As shown, the supports at the ends of the legs are carried above the core and form supports for a bar or plate 14 which bridges the gap between 40 the planes of the faces at a point spaced above the plane of the core legs as shown in Fig. 2.

Base 12 and plate 14 carry bearings for a spindle 15 located in said axis, said spindle carrying the armature 16 having a peripheral contour which includes faces complementary to the polar faces of the core, these armature faces being preferably spaced a suitable distance from the polar 50 faces. The armature is of laminated form, with the sheets preferably having the contour of the peripheral contour of the armature, thus providing the armature faces by the adjacent edges of the laminations.

60 Since the armature is pivotally mounted on an axis forming the focal point of the polar faces, the armature is movable relative to the polar faces without possibility of contact with the faces or any abutments carried thereby, so that possibility of chatter-

ing is eliminated. And as both core and armature are of laminated structure, the usual humming produced in the presence of alternating current operation is greatly reduced or entirely absent.

70 Since the structure is operative as a relay the armature must be movable into and out of a predetermined position. This is had by connecting a coil spring 17 to the spindle and to a pin depending from plate 14, the connection being such as to cause the spring to tend to move the armature out of its attracted position in the magnetic field and to a deflected position—counter-clockwise in Fig. 3—the limit of movement 75 in this direction being provided by bringing a contact 18—carried by an arm 18^a projecting from the spindle—into contact engagement with a contact 19 carried by a bracket 20 supported by and insulated from the base, contact 19 being preferably carried by a leaf spring 19^a which tends to cushion the engagement when made. The movement of the armature from this latter position into attracted position is provided 80 by the activity of the magnetic field when the coils are energized, the movement being in opposition to the tension of spring 17 and in a direction clockwise in Fig. 3, the latter view indicating the position of the 85 armature with the field active, contacts 18 and 19 being separated at this time.

90 21 indicates a member for holding the coils in position.

The indicating structure is provided by 100 an arm 22 carried by the spindle and which carries a flat plate 22^a at its free end, and a plate-like member 23 positioned above the coils and extending beneath the path of movement of plate 22^a (Fig. 2). The relative arrangement of the parts may be 105 such that plate 22^a may be located above member 23 when the armature is in the position of Fig. 3, or by changing the position of the arm, this position may be had when 110 the armature is shifted to its opposite extreme—the form shown in the drawings is preferred.

115 The visible signal is given by the exposure of a suitable indication, which may be carried by plate 22^a or by member 23, and is preferably of a type to call specific attention to the indication when the circuit through the coils is broken. For this purpose the indication may be in the form of 120 a distinguishing marking—as for instance a colored disc—placed on member 23 in a position to be hidden by plate 22^a when the armature is in the position of Fig. 3—the exposure opening of the casing (not shown) 125 being opposite the indication—or the mark may be on plate 22^a with the casing opening positioned to provide exposure of the mark when plate 22^a has been shifted to the opposite extreme of its length of movement. 130

Obviously, the signal may be provided when the circuit is unbroken, by placing the mark on plate 22^a and locating the exposure opening above this point in Fig. 3. And as will be understood, both plate 22^a and member 23 may each carry marks differing from each other, so that with the sight opening properly positioned, one mark will be visible with the circuit unbroken and a different 10 mark visible when break in the circuit occurs.

While I have referred to the limiting devices as in the form of contacts 18 and 19, it will be understood that the invention is 15 not limited in this respect, since these elements—used in the present embodiment as the elements of a circuit make and break means—may be simply stop elements of any preferred form. Where operative as make 20 and break structures, the leads may be operatively connected to spring 19^a and the spindle or arm 18^a in any preferred manner.

For illustrating the general operation, I have shown, in Fig. 4, a diagrammatic view 25 of a simple circuit which includes a source of electrical supply M, a lamp L and a switch S, coils 11 being shown diagrammatically, as is the armature. As will be seen, the coils and lamp are in series, so that while 30 the circuit remains unbroken the armature will be held to break an auxiliary circuit between contacts 18 and 19, the auxiliary circuit being shown as including a gong or bell G. While the integrity of the circuit 35 through the lamp—the main circuit—remains unimpaired, the armature will be held in position to maintain the auxiliary circuit broken, breaking of the main circuit permitting shifting of the armature to complete 40 the auxiliary circuit and sound the audible signal, the changes in position of the armature affecting the visual signals in a predetermined manner, as pointed out.

As will be readily understood, a number 45 of these main circuits may be connected in parallel, each having its individual relay, and the auxiliary circuits may be so arranged as to be operative on a single audible signal. This is permitted because of the 50 fact that the relay operations are made noiseless—or substantially so—by the particular form of the relay, and the number which may be present at any point becomes immaterial, the audible signal calling attention to the fact that one or more of the main 55 circuits has been impaired, and a rapid inspection of the indicators of the relays will determine the particular circuit involved. Upon restoring the circuit, the relay gives 60 immediate note of the fact through the movement of the armature—an advantage in the control of running lights, in case of the use of a single lamp circuit, since it automatically signals the rapidity with which the 65 orders for repairs have been carried out.

As will be readily understood, the use of the laminated armature, pivoted in the axis of the magnetic field-forming elements, does not require that the polar and armature 70 faces pass into contact. In practice, a considerable space is left between the opposing faces, thus not only eliminating all possibility of production of noises through contact, but at the same time eliminating the 75 possibility of dust bridging the space and tending to retard the movements of the relay. The mounting of the armature is such as to provide easy movement of the armature even with comparatively small currents, thus making the relay sensitive in action and of comparatively small size. In this connection, it may be noted that a standard relay in service, employed on 110 and 120 volt circuits has the diameter of its 80 base 12 three inches.

While I have herein shown and described a preferred embodiment of the invention and ways in which it may be carried out, it will be readily understood that changes or 85 modifications therein may be found desirable or necessary in meeting the exigencies of use, and I desire to be understood as reserving the right to make all such changes or modifications as may be found desirable or essential, in so far as the same may fall 90 within the spirit and scope of the invention as expressed in the accompanying claims.

Having thus described my invention, what I claim as new is:

1. An alternating current relay comprising a base, a stator carried by said base and including an electromagnet and a laminated core terminating in oppositely positioned poles, a rotor carried by said base and including opposed bearings located between the poles of the stator, an armature and its shaft journaled therein, the armature being movable into attracted and deflected positions upon energization and deenergization of the said electromagnet, cooperating contact elements including a stationary contact element carried by the said base and a movable contact element carried by the said armature shaft, and a resilient device active for shifting said armature and shaft to its deflected position and for effecting engagement of said contact elements upon deenergization of the electromagnet, the said contact elements forming a means for limiting the deflected position of the armature and 110 for closing an electric circuit.

2. An alternating current relay comprising a base, a stator carried by the base and including a field electromagnet and a core terminating in oppositely positioned poles, a bearing plate carried by the said base and spaced therefrom, aligned bearings in the said base and plate respectively, a rotor including an armature having a shaft journaled in the said bearings, the armature be- 115 120 125 130

ing movable into attracted and deflected positions upon energization and deenergization of said electromagnet, cooperating contact elements including a resiliently mounted stationary contact element carried by the base and a contact element connected to said armature shaft for movement therewith, and a spring surrounding the said armature shaft and anchored at opposite ends to the 10 said shaft and to the said bearing plate, the said spring being active for shifting the armature to its deflected position and for effecting engagement of said contact elements upon deenergization of the electromagnet, the said contact elements forming 15 a means for limiting the deflected position of the armature and for closing an electric circuit.

3. An alternating current relay compris-

ing a base, a stator carried by said base and 20 including an electromagnet and a laminated core terminating in oppositely positioned poles, a rotor carried by said base and including opposed bearings located between the poles of the stator, an armature and its 25 shaft journaled therein, the armature being movable into attracted and deflected positions upon energization and deenergization of the said electromagnet, cooperating contact elements including a stationary contact element carried by the said base and a 30 movable contact element carried by the said armature shaft, and a resilient device active for shifting said armature and shaft to its 35 deflected position.

In testimony whereof I have hereunto set my hand.

FRANK W. WOOD.
